[57] CLAIM

The ornamental design for a scanner, as shown and described.

DESCRIPTION

FIG. 1 is a perspective view of the front, top and right side of a scanner showing our new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a perspective view similar to FIG. 1 with a sliding front cover moved to the right;

FIG. 9 is a perspective view similar to FIG. 1 with a top cover removed;

FIG. 10 is a front elevational view thereof;

FIG. 11 is a right side elevational view thereof;

FIG. 12 is a left side elevational view thereof;

FIG. 13 is a top plan view thereof;

FIG. 14 is a rear elevational view thereof; and,

FIG. 15 is a perspective view similar to FIG. 1 with the sliding front cover moved to the right and the top cover removed.
